UNITED STATES PATENT OFFICE.

FRANCIS GADDIS, OF MERRICK, NEW YORK.

AIRCRAFT.

Application filed May 3, 1926. Serial No. 106,516.

This invention relates to air craft, and has especial reference to heavier than air craft.

An object of the present invention is to provide an air craft with a novel means for lifting or causing the ascension of the craft and for sustaining the same in the air.

To provide an air craft with an efficient form of lifting apparatus which causes the craft to ascend after the manner of a helicopter, and in which there is provided a maximum lifting surface with a minimum resistance of the main lifting and sustaining elements, is another object of the invention.

Another object of the invention is to provide a heavier than air craft with means for lifting or causing the ascension of the craft after the manner of a helicopter, and a second means which supplements the first mentioned means in lifting the craft and which also serves for causing the translatory movement of the craft.

With the foregoing and other objects in view, the invention resides in the particular provision, relative disposition and operation of the parts.

The nature of the invention and its distinguishing features and advantages will appear when the following specification is read in connection with the accompanying drawings, in which—

Figure 1 is a side elevation of an air craft embodying the present invention.

Fig. 2 is a plan view.

Fig. 3 is a transverse sectional view taken on the line 3—3 of Fig. 2.

Fig. 4 is a view of one of the stators and the rotor which is shown in section, and also illustrating the manner in which it travels around with respect to the stator.

In the illustrated embodiment there is shown a heavier than air craft of the hydro-aircraft type. The craft includes a main supporting structure or body 10 which supports the lifting means, the supplemental lifting and propelling means, and the engines which operate the said means for lifting and propelling the craft. The structure or body 10 is in the form of a boat hull and is equipped with a landing gear in the form of shock absorbers 11 fore and aft of the body 10. The body is also provided with means for steering the same in the form of a rudder 12 which is operated by any suit-

able operating means such as the one indicated at 13.

The main lifting means which serves for lifting craft substantially vertically and for sustaining the craft in the air, in the present instance includes stators 14 which are arranged in pairs above the body 10, as shown most clearly in Figs. 1 and 3. The stators are fixedly supported from supports 15 mounted on the top of the body 10. Associated with each pair of stators 14 is a lifting rotor 16 in the form of an oblong panel which is supported by and bears a sliding relationship to a driving element or shaft 17 supported for rotation by bearings 18 of the supports 15. Each shaft 17 is arranged eccentrically with respect to its related pair of stators 14 for a purpose to appear. The rotor 16 has the opposite ends thereof respectively associated with the stators 14, the opposite side edges of the rotor being provided with anti-friction rollers 19 which roll in contact with the related stator, as shown most clearly in Fig. 4. As stated each rotor has a sliding relation to its shaft and this is obtained by having the rotor extend through the shaft, as shown most clearly in Fig. 4. By having the shaft 17 arranged eccentrically with respect to its related stators 14 and the rotor 16 slidable with respect to the shaft 17, it is possible to obtain a greater rotor surface at one side of the longitudinal axis of rotation than at the other side thereof. Each stator is not truly circular but is irregular in form so as to permit the rotor to have rotational as well as sliding movements. It is to be noted that the rotors 16 are disposed longitudinally of the body 10 and each is of a length so as to extend substantially the length of the body 10. The rotors 16 are mainly relied upon for lifting the craft and for sustaining the same in the air, and when in operation lifting the craft substantially vertically after the manner of a helicopter.

In order to augment the lifting effect of the rotors 16, and also to cause the translatory movement of the craft there are provided pairs of stators 20 at each side of the body 10 which will be disposed below the stators 14. The stators 20 are similar in construction to the stators 14 and are movably held in place by brackets 21 which are supported from the body 10 by a transverse support 22. Associated with each pair of sta-

tors 20 is a lifting and propelling rotor 23 similar to the rotors 16 but somewhat shorter in length. Two rotors 23 are associated with and operated by a driving element or 5 shaft 24 which extends transversely through the body 10 as shown most clearly in Fig. 3. Each of the rotors 23 is slidable with respect to its shaft 24 and operates in the same manner in which the rotors 16 operate, each rotor 10 23 having anti-friction rollers 25 which roll in contact respectively with the stators 20. Each shaft 24 is supported for rotation in bearings 26 carried by the brackets 21 and the body 10. Each shaft 24 is associated 15 with two pairs of stators 20 which are arranged in transverse alignment, and the shaft 24 is arranged eccentrically with respect thereto. It follows therefore that when the rotors 23 are in operation each will 20 present a greater surface at one side of its axis of rotation than at the opposite side thereof.

In order to cause the rotation of the rotors 16 and 23, any suitable power system 25 may be employed and in the present instance there is shown an engine 27 which may be of any preferred type such as an internal combustion engine which includes a drive shaft 28 extending rearwardly, as shown 30 most clearly in Fig. 2. Motion is transmitted to the shafts 17 by virtue of the intervention of sprockets 29 and 30 respectively on the shafts 17, 28, and countershaft 28', and chains 31, each of which operates in 35 conjunction with a sprocket 29 and sprocket 30. Motion is transmitted to the countershaft 28' from shaft 28 by virtue of the gears 30'. The driving connection between the drive shaft 28 and the shafts 17 is such that 40 the rotors 16 will be rotated in opposite directions. A suitable clutch 32 is employed so that the rotor 16 may be stopped from rotating while the engine is running. The rotors 23 are caused to rotate in the same 45 direction by virtue of the intervention of driving connections between the drive shaft 28 and the shafts 24. In the present instance the said driving connections between these 50 shafts includes a bevel gear 33 on the shaft 28 which meshes with a similar gear 34 on a shaft 35 rotatably supported in suitable bearings, the said shaft 35 having a bevel gear 36 which meshes with a similar gear 37 on the rear shaft 24. The two shafts 24 are 55 rotated in the same direction by virtue of the use of sprockets 38 respectively on the shafts 24 and a chain 39 which encircles the sprockets 38. A suitable clutch 40 in the drive shaft 28 allows the rotors 23 to be 60 stopped while the engine is running.

In order to change the positions of each of the stators 20 from the position shown in Fig. 1 in which the rotors 23 will augment the lifting action of the rotors 16, to a position in which the rotors 23 will cause the

translatory movement of the craft means presently to be described, is provided. Each stator 20 is provided with a gear segment 41 which has in meshing engagement therewith a pinion 42. Shafts 43 each carry four of 70 the pinions 42. Each shaft 43 is arranged transversely of the body 10 and is supported in suitable bearings in the brackets 21 and body 10. Similar movement is imparted to both of the shafts 43 by virtue of a hand 75 wheel 44 on one of the shafts, and by virtue of the intervention of sprockets 45 respectively on the shafts 43 and a chain 46 which encircles the sprockets 45. When the stators 23 are in the positions shown in Fig. 1 80 their rotors 23 in operation will cause a lifting action because their greater surfaces will be operating against the air in a downward direction, whereas when the stators 23 are moved one-quarter of a revolution counter-clockwise, the greater surfaces of the rotors 23 at one side on their axes will be operating against the air mainly in a rearward direction. In the latter case the craft will 85 have imparted thereto translatory movement as distinguished from upward movement.

From the foregoing, it will be apparent that the rotors 16 may be operated independently of the rotors 23 for causing the ascension of the craft, although if desired the rotors 23 as well as the rotors 16 may be set in motion at the same time for lifting the craft and sustaining the same in the air, also for descending. It will also be apparent that by 90 adjusting the stators 20 a change of function of the rotors 23 will be obtained in that the rotors instead of serving for lifting the craft, will cause its translatory movement.

I claim:

1. In an air craft, a supporting body, oblong lifting rotors extending longitudinally above the body, and oblong lifting and propelling rotors extending laterally from the sides of the body, there being one at the front and one at the rear on each side of the body.

2. In an air craft, a supporting body, oblong lifting rotors extending longitudinally above the body substantially the length of the body, and oblong lifting and propelling rotors extending laterally from the sides of the body, there being one at the front and one at the rear on each side of the body.

3. In an air craft, a main supporting structure, lifting panels each of which rotates on an axis disposed longitudinally above the supporting structure, and lifting and propelling panels each of which rotates on an axis disposed laterally on each side of the supporting structure, there being one at the front and one at the rear on each side of the supporting structure.

4. In an air craft, a main supporting structure, adjustable stators arranged in

5 pairs on the supporting structure, a lifting rotor associated with each pair of stators, means for effecting the rotation of the rotors, and means for effecting the adjustment 5 of said stators to vary the lifting action of the rotors.

10 5. In an air craft, a main supporting structure, adjustable stators arranged in pairs on the supporting structure, a lifting rotor associated with each pair of stators, means for effecting the rotation of the rotors, said means including a shaft for each rotor with which it bears a slideable relationship, each shaft arranged eccentrically with 15 respect to its related pair of stators, and means for effecting the adjustment of the stators with respect to their rotors to vary the lifting action of the rotors.

20 6. In an air craft, a main supporting structure, stators arranged in pairs on the supporting structure, a lifting rotor associated with each pair of stators so as to extend laterally with respect to the supporting structure, and means for effecting the rotation 25 of the rotors in the same direction.

30 7. In an air craft, a supporting body, lifting rotors, a pair of stators associated with each of said lifting rotors, lifting and propelling rotors, a pair of stators associated with each of said lifting and propelling rotors, means for effecting the rotation of lifting 35 rotors, and means for effecting the rotation of the lifting and propelling rotors.

35 8. In an air craft, a supporting body, lifting rotors, a pair of stators associated with each of said lifting rotors, lifting and propelling rotors, a pair of adjustable stators associated with each of said lifting and propelling rotors, means for effecting the 40 rotation of lifting rotors, means for effecting the rotation of the lifting and propelling rotors, and means for effecting the adjustment of the adjustable stators to vary the

lifting and propelling action of the lifting and propelling rotors. 45

9. In an air craft, a supporting body, lifting rotors, a pair of stators associated with each of said lifting rotors, lifting and propelling rotors, a pair of stators associated with each of said lifting and propelling rotors, means for effecting the rotation of lifting rotors in opposite directions, and means for effecting the rotation of the lifting and propelling rotors. 50

10. In an air craft, a supporting body, lifting rotors, a pair of stators, associated with each of said lifting rotors, lifting and propelling rotors, a pair of stators associated with each of said lifting and propelling rotors, and means for effecting the rotation of the lifting and propelling rotors in 55 the same direction. 60

11. In an air craft, a supporting body, lifting rotors, a pair of stators associated with each of said lifting rotors, lifting and propelling rotors, a pair of adjustable stators associated with each of said lifting and propelling rotors, means for effecting the rotation of lifting rotors in opposite directions, means for effecting the rotation of the 65 lifting and propelling rotors, and means for effecting the adjustment of the adjustable stators to vary the lifting and propelling action of the lifting and propelling rotors. 70

12. In an air craft, a supporting body, lifting rotors, a pair of stators associated with each of said lifting rotors, lifting and propelling rotors, a pair of adjustable stators associated with each of said lifting and propelling rotors, means for effecting the 75 rotation of lifting rotors in opposite directions, and means for effecting the rotation of the lifting and propelling rotors, in the same direction. 80
